CLAIM

The ornamental design for a base power connector housing as shown and described.

DESCRIPTION

FIG. 1 is a perspective view of a base power connector housing;

FIG. 2 is a reverse perspective view of the base power connector housing;

FIG. 3 is a left side view of the base power connector housing;

FIG. 4 is a right side view of the base power connector housing;

FIG. 5 is a top side view of the base power connector housing; and,

FIG. 6 is a bottom side view of the base power connector housing.

The broken lines in the drawings depict portions of the base power connector housing that form no part of the claimed design. Additionally, the dot-dashed broken line in FIG. 2 and FIG. 6 depicts a boundary of the claimed design; the dot-dashed broken line forms no part of the claimed design.

1 Claim, 6 Drawing Sheets
